DESIGN FOR AN OIL BURNER

Robert F. Andler, Rutherford, N. J., assignor to Electrol Incorporated, Clifton, N. J., a corporation of Delaware

Application June 30, 1937, Serial No. 70,140

Term of patent 14 years

To all whom it may concern:

Be it known that I, Robert F. Andler, citizen of the United States, residing at Rutherford, in the county of Bergen and State of New Jersey, have invented a new, original, and ornamental Design for an Oil Burner, of which the following is a specification, reference being had to the accompanying drawings, forming part thereof.

Fig. 1 is a front perspective view of an oil burner shown my new design; and

Fig. 2 is a rear perspective view thereof.

I claim:

The ornamental design for an oil burner as shown.

ROBERT F. ANDLER.
